F. M. WATKINS.

CENTRIFUGAL EXTRACTOR.

APPLICATION FILED AUG. 9, 1916. RENEWED OCT. 26, 1917.

1,325,064.

Patented Dec. 16, 1919.

INVENTOR
Frank M. Watkins.
W. J. Peck.
ATTY.

UNITED STATES PATENT OFFICE.

FRANK M. WATKINS, OF CINCINNATI, OHIO.

CENTRIFUGAL EXTRACTOR.

1,325,064.

Specification of Letters Patent. Patented Dec. 16, 1919.

Application filed August 9, 1916, Serial No. 113,879. Renewed October 26, 1917. Serial No. 198,741.

To all whom it may concern:

Be it known that I, FRANK M. WATKINS, a citizen of the United States, and resident of Cincinnati, in the county of Hamilton and State of Ohio, have invented certain new and useful Improvements in Centrifugal Extractors, of which the following is a full, clear, and exact description, reference being had to the accompanying drawing, 10 forming part of this specification.

My invention relates to devices for extracting liquids from various substances and more particularly to that class of such devices wherein centrifugal force is employed 15 for removing the water from clothes and other articles which have been washed, though it is capable of advantageous use for a variety of other purposes as will be readily apparent.

20 One object of my invention is the provision of means whereby, when articles have been placed within the device and subjected to centrifugal force, such articles may be easily removed and the device re-loaded and 25 again set in operation in a very small fraction of the time hitherto required for the unloading and re-loading of centrifugal extractors.

Another object of my invention is the provision of a device in which the most delicate 30 fabrics may be subjected to centrifugal force without risk of injury.

Another object of my invention is to so construct the device that during the extracting operation, a large amount of air will be forced through the contents of the machine thereby thoroughly aerating the articles and materially assisting in removing the moisture.

40 The novelty of my invention will be hereinafter more fully set forth and specifically pointed out in the claims.

In the drawings:

Figure 1 represents a side view of a completely organized machine embodying my invention in a suitable form for use in laundries where large quantities of clothes are handled.

Fig. 2 is a side elevation of the wringer 50 basket, and associated parts removed from the machine.

Fig. 3 is a view corresponding to Fig. 2, showing the false bottom, partitions, and at-

tached parts elevated out of the basket and in proper position for unloading.

Fig. 4 is a plan view, partly broken away, of the interior parts of the basket.

The same numerals of reference are used to indicate identical parts in all the figures.

To enable those skilled in the art to which my invention pertains to comprehend the same I have shown, as one form in which my invention may be embodied, a base 1, Fig. 1, provided with a curb 2 and a series of standards 3 supporting a superstructure 4.

Suitably journaled within the superstructure 4 and base 1 is a vertical shaft 5 shown in dotted lines, Fig. 1, which is driven by a pulley 6 through the medium of a belt passed over guide pulleys 7 and drive pulley 8 mounted on and driven by a horizontal shaft 9 which is preferably located near the lower part of the machine and supported between inboard bearing 10 and outboard bearing 11.

The shaft 9 is provided with tight and loose pulley mechanism 12 so that its rotation may be started or stopped at will.

A suitable brake mechanism 13 is mounted on the superstructure 4 and provided with a brake shoe 14 which is adapted for contact with the pulley 6 and arrest its motion after the drive belt has been shifted to the loose pulley.

As shown in Figs. 2 and 3 the lower end of the vertical shaft 5 is provided with a basket 15 which is preferably formed of sheet metal and has a flat bottom with an inclined side wall, the upper edge of the basket being preferably turned outward to form a flange whereby the basket is maintained in proper form.

A hub 16 provided with an operating groove 17 at its upper end is mounted free to slide on the shaft 5 and carries, at its lower end a disk 18 which latter is of a diameter equal to the inside diameter of the bottom of the basket 15 and when in the position shown in Fig. 2, the disk 18 becomes a false bottom for the basket 15.

A series of partitions 19 are secured to the hub 16 and disk 18, these partitions being of such size that when lowered into the basket 15 as shown in Fig. 2, the partitions contact with the inner face of the tapered wall of the basket and extend a very slight distance above the top edge of the said basket.

A ring 20 shown more clearly in Fig. 4 is secured to the upper edges of the partitions 19 and is of an outside diameter approximately equal to the outwardly extending 5 flange of the basket 15 and when occupying the position shown in Fig. 2 a very narrow annular opening is provided between the ring 20 and the basket 15 and the liquid being expressed from the contents of the 10 basket escapes through this opening into the base 1, from which it is drained after the usual manner of draining centrifugal extractors.

In order to provide a power operated 15 means for elevating the hub 16 and its associated parts I have shown an elevating arm 21 Fig. 1 which is raised and lowered by the lead screw 22, which latter is adapted to be operated through an ordinary train of bevel 20 gears 23 shown in dotted lines, Fig. 1. Two of the bevel gears 23 are mounted on a horizontal shaft 24 which latter is provided with a splined clutch member controlled through the link 25 and handle 26. A vertical shaft 26 27 provided with throwout fingers 28 is mounted adjacent the elevating arm 21 in such manner that when the arm 21 has reached its upper or lower position the vertical shaft 27 will be automatically operated 30 to disengage the drive for the lead screw 22 thereby preventing injury to the machine.

It will be evident that when my invention is used in comparatively small sizes the power elevating mechanism may be dispensed with and the hub 16 and associated parts may be elevated by hand.

The operation of the device as shown in Fig. 1 is as follows: The guard doors 29 are slid in channels thus giving access to the 40 interior of the machine and permitting the introduction into the basket 15 of the articles to be subjected to centrifugal force, the arm 21 in the meanwhile being in the position shown in Fig. 1 with the finger 30 45 disengaged from the operating groove 17 of the hub 16 so as not to interfere with the oscillating motion of the basket in operation, and the interior parts of the basket 15 being in the position shown in Fig. 2.

50 The tight and loose mechanism 12 is now operated to impart rotation to the vertical shaft 5 through the medium of the drive belt, the guard doors in the meanwhile having been closed. The revolution of the vertical shaft 5 and with it the basket 15 and contents is continued for a definite period of time after which the rotation is stopped by again operating the tight and loose pulley mechanism to shift the drive belt into 55 the loose pulley and the brake mechanism 13 is operated, thereby applying the brake shoe 14 to the pulley 6 and bringing the vertical shaft 5 and its associated parts to rest.

To remove the contents from the basket 60 15 the handle 26 is operated to engage the

gear train 23 and cause the rotation of the lead screw 22 thereby raising the arm 21 and with it the hub 16, false bottom 18, and partitions 19 as well as the ring 20. During the rotation of the basket 15 the contents, particularly if they be articles of clothing become very much condensed in the basket and intermingle one with another to such an extent that heretofore it has been exceedingly difficult to unload the basket.

With my device the raising of the false bottom and the partitions out of the tapered basket releases the contents and permits the basket to be emptied immediately, the operator reaching through the opening in the ring 20 and pressing against the contents between any pair of the partitions 19, forces the contents toward himself and drops them into any suitable container which he has placed immediately in front of the base 1 and then turns the ring 20 and its associated parts a quarter of a turn and removes the contents from that section and so on until all of the contents have been removed whereupon the hub 16 and its associated parts are again lowered from the position shown in Fig. 3 to that shown in Fig. 2 through the medium of the mechanism before described, whereupon the basket may be again loaded, the brake released, and the vertical shaft set in motion as before described.

It is to be observed that when the drive belt which passes over the tight and loose pulleys, is on the loose pulley and the vertical shaft 5 is at rest, the horizontal shaft 24 is 100 in motion, being driven through the medium of a vertical belt and a pair of pulleys, the lower of which is attached to the loose pulley on the shaft 9, so that the lead screw 22 may be rotated in either direction to elevate 105 or lower the arm 21 and with it the hub 16 and its associated parts.

It will be apparent that a variety of means may be employed for operating the parts herein described without in any way departing from the spirit of my present invention and further that the number of partitions which are adapted to be lowered into the basket, the arrangement of these partitions, the construction, and the construction and arrangement of the parts associated with these partitions form only an incidental part of the invention and may be greatly varied or modified to suit conditions existing at any particular time or place or in any particular 115 line of business to which centrifugal extractors are applicable or in which they are used.

Particular attention is to be paid to the fact that the side walls of the basket are preferably imperforate and present a perfectly smooth surface to the articles being subjected to centrifugal force.

While I have shown the basket 15 arranged with its large diameter upward and secured to the vertical shaft 5 and while 180

I have shown the false bottom 18 as being solid and the ring shaped cover 20 as being provided with a large central opening, it is evident that these parts may be all reversed 6 and the basket inverted in which case the basket 15 would be mounted to slide vertically on the shaft and its end partly cut out to afford means for introducing articles into the basket, and a disk of a diameter 10 equal to the large diameter of the basket may be fixed to the vertical shaft in such manner that when it is desired to unload the extractor the basket would be raised thereby leaving its contents on the disk from which 15 such contents could be easily removed, and in carrying the construction to a complete form a false top of an annular form, could be secured to the vertical shaft and partitions interposed between said false top and 20 the lower disk so that when the basket would be raised to unloading position the articles therein would be positively extracted therefrom. As a further modification the partitions 19 could be attached to the 25 basket itself and be raised from among the contents when the basket is elevated.

It is to be observed that during the operation of the machine the contents of the basket will be localized adjacent to the outlet for the moisture, the mere weight of the 30 contents serving to accomplish this localization, and that the rapid rotation of the baskets and the partitions will convert the structure into a form of centrifugal blower, 35 the result being that a large volume of air will be forced through the contents of the basket and, due to the localization of the contents, the air will be forced through a substantially uniform section of contents, 40 thereby thoroughly aerating the latter and assisting in the removal of the moisture.

Having thus fully described my invention, I claim:

1. In a centrifugal extractor the combination of a basket having an imperforate inclined side wall, whereby when centrifugal force is applied the contents exhibit tendencies of being thrown out of the basket, 45 means for maintaining contents within said basket during the application of centrifugal force, while permitting the escape of liquid from the basket, radial partitions attached to said means, and moving with the same and lying within said basket when in operating position, and means for causing the relative axial movement between said basket and said maintaining means.

2. In a centrifugal extractor the combination of a basket with an imperforate inclined side wall, whereby when centrifugal force is applied the contents exhibit tendencies of being thrown out of the basket, 50 means for maintaining contents within said basket against the action produced by and during the application of centrifugal force,

while permitting the escape of liquid from the basket, a disk bearing a fixed relation to said maintaining means and occupying a position adjacent the small diameter of said basket when in operating position, and 55 means for causing the relative axial movement between said disk and maintaining means and said basket and whereby articles which have been introduced into said basket and subjected to centrifugal force may be 60 removed therefrom.

3. In a centrifugal extractor the combination of a basket having an imperforate inclined side wall, whereby when centrifugal force is applied the contents exhibit 65 tendencies of being thrown out of the basket, means for maintaining contents within said basket against the action of centrifugal force and during the application of centrifugal force, while permitting the escape of liquid from the basket, a disk bearing a fixed relation to said maintaining means and occupying a position adjacent the small diameter of said basket when in operating position, radial partitions between said disk 70 and said maintaining means, and means for causing a relative axial movement between said basket and said disk and associated parts whereby articles which have been introduced into said basket and subjected to 75 centrifugal force may be removed therefrom.

4. In a centrifugal extractor the combination of a basket having an inclined imperforate side wall, whereby when centrifugal force is applied the contents exhibit tendencies of being thrown out of the basket, 80 means for maintaining contents within said basket against the action of centrifugal force acting along the lines of the inclined wall of the basket, while permitting the escape of liquid from the basket, a false bottom, and means for raising said maintaining means and said false bottom out of 85 said basket to release and permit the removal of the contents.

5. In a centrifugal extractor the combination of an imperforate frusto-conoidal basket, a false bottom for said basket, radial partitions attached to said false bottom, a ring shaped cover attached to said partitions, and occupying a position adjacent the large diameter of the basket when in operative position thus coöperating with the basket to maintain its contents therein and permit the escape of liquid, and means for raising said false bottom and associated parts out of said basket.

6. In a centrifugal extractor the combination of a basket having an imperforate inclined side wall, means for maintaining articles within said basket, against the action of centrifugal force and coöperating with said basket to form an outlet for liquid, means for separating the articles introduced into said basket into a plurality of groups,

and means for causing a relative axial movement between said basket and said maintaining means whereby the articles may be released from said basket.

7. In a centrifugal extractor the combination of a basket having an imperforate inclined side wall which is maintained in position by a support in the small diameter thereof, a load manipulating device mounted to pass through the large end of said basket and coöperating with the large end thereof to form an outlet for liquid, and means whereby said load manipulating devices and said basket may be moved with relation to each other to release the load from the basket, and means for operating the basket.

8. In a centrifugal extractor a basket structure having an imperforate inclined side wall, means for maintaining contents within said basket during its operation said means coöperating with the large end of said basket to form an outlet for liquid adjacent the large end, and means within the

basket comprising partitions for forcing air 25 through the contents of the basket during its operation.

9. In a centrifugal extractor a basket having an inclined side wall, a combined load retaining and releasing device normally 30 mounted therein, and coöperating therewith to form an outlet for liquid, and means for causing relative movement between said basket and said device for the release of the load.

10. In a centrifugal extractor a basket having an inclined side wall with an unobstructed opening at its large end, a load manipulating device normally located within said basket and coöperating therewith to 40 form an outlet for liquid and air-forcing elements comprising blades or partitions within said basket during its operation for forcing air through the load.

FRANK M. WATKINS.
